Primary Examiner — Sandra S Snapp*Assistant Examiner* — Mehri F Bajoul*(74) Attorney, Agent, or Firm* — Slater Matsil, LLP(57) **CLAIM**

The ornamental design for a packing box for a trash bag, substantially as shown and described.

DESCRIPTION

FIG. 1 is a perspective view of a packing box for trash bag with a lid showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top view thereof;

FIG. 8 is a bottom view thereof;

FIG. 9 is a top perspective view of the packing box for trash bag with the lid removed for ease of illustration;

FIG. 10 is a bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is an exploded top perspective view of the packing box for a trash bag of FIG. 1; and,

FIG. 18 is an exploded bottom perspective view thereof.

The broken lines in the drawings illustrate portions of the packing box that do not form part of the claimed design.

1 Claim, 18 Drawing Sheets(56)
